UNITED STATES PATENT OFFICE.

HARRY W. HARDINGE, OF NEW YORK, N. Y., ASSIGNOR TO HARDINGE CONICAL MILL COMPANY, OF NEW YORK, N. Y., A CORPORATION OF NEW YORK.

SIZING APPARATUS.

1,149,826.

Specification of Letters Patent. Patented Aug. 10, 1915.

Application filed December 23, 1914. Serial No. 878,810.

To all whom it may concern:

Be it known that I, HARRY W. HARDINGE, a citizen of the United States residing at New York, in the county and State of New York, have invented certain new and useful Improvements in Sizing Apparatus, of which the following is a full, clear and exact description.

In grinding or finely dividing ores and other materials, some of the particles produced are too large for their intended use or for the particular treatment to which they are afterward to be subjected, and in some cases the proportion of particles of excessive size is so large as to cause an appreciable loss of values. If the attempt is made to obviate the difficulty by subjecting the entire material to longer or more powerful grinding action we are met by the fact that the output of the machine per unit of time is reduced or the amount of power consumed is increased, or both; and, moreover, in thus minimizing the proportion of particles that are too large the proportion of particles that are or may be too small is increased. The best solution of the problem is to remove from the disintegrated material the large particles so that they can be returned to the grinding apparatus for further reduction.

My present invention is designed to provide a simple, cheap, and withal thoroughly effective apparatus for thus separating the larger particles from the smaller, and, preferably, also returning the former to the grinding or disintegrating mill for further grinding.

To these and other ends the invention consists in the novel features of construction and combinations of elements hereinafter described and claimed.

In its preferred form, my invention comprises a rotary container or receptacle from which the disintegrated material is discharged in the form of fine particles. This receptacle may be the tube mill in which the grinding is done, in which case I employ preferably a "conical mill" of the type described in my prior patent No. 908,861, dated January 5, 1909, as it has been found by experience that in a well designed mill of that type the percentage of excessively

large particles is smaller under similar conditions of use than in other types of mills in common use. The receptacle referred to, for example a conical grinding mill, is provided with an outlet element of tubular form, preferably cylindrical, which outlet element is usually one of the trunnions on which the mill revolves. The inner surface of such trunnion is provided with a plurality of pockets, channels, or grooves extending in a generally axial direction and preferably formed by ribs or narrow blades attached to the said inner surface. As the disintegrated material is discharged, being carried by flotation on a stream of water flowing through the mill, most of the large particles which find their way to a point near the inner orifice of the outlet trunnion are too heavy to float and so sink back into the mill; but others, buoyed up by the outflowing slime, enter the trunnion and, although as they move along they may be settling to the bottom of the stream, their downward progress is slow, and hence, with the ordinary form of outlet trunnion, they are carried on out and are discharged. With the ribs or grooves in the trunnion, as provided in my scheme, the revolving grooves carry the outwardly flowing material upwardly and permit only the surface stratum of the stream to escape at once, thus giving the larger particles ample time to sink well below the surface. Then, at a suitable point, the grooves come into the path of a jet of water or other fluid directed toward the interior of the mill, with the result that the material carried up by the grooves or ribs, composed for the greater part of particles too coarse to float on the surface of the water, are propelled or washed back into the mill for further subjection to the grinding or disintegrating process there going on.

In the accompanying drawing I have illustrated, somewhat diagrammatically, an apparatus embodying the above features and operating as described.

Referring now to the drawing, Figure 1 shows the apparatus in vertical longitudinal section. Fig. 2 is a cross section on line 2—2 of Fig. 1, looking in the direction of the arrow.

The grinding mill 10, of the conical type

described in my prior patent above mentioned, has an inlet trunnion 11 and an outlet trunnion 12 mounted rotatably in suitable bearings on the standards or supports 5 13, 14. The mill or drum 10 is rotated by means of a gear 15, fixed adjacent to the inlet trunnion and driven by any suitable means, not shown. The partially disintegrated ore or other material is discharged 10 into the mill, along with a stream of water, by means of an inlet chute 16 extending into the inlet trunnion, and the finely divided material issues from the outlet trunnion into a suitable launder 17.

15 As shown more clearly in Fig. 2, the inside of the outlet trunnion is provided with a series of longitudinally extending ribs 18, secured to the trunnion in any convenient manner and, preferably, inclined as shown, 20 that is, toward the direction of rotation of the trunnion, which direction in the present instance is counterclockwise, as seen in Fig. 2. Grooves or channels are thus provided which are somewhat narrower at their 25 tops than would be the case if the ribs were strictly radial in direction.

As the stream of slime flows through the outlet trunnion any large particles that may be mixed with it are slowly sinking, and 30 before they reach the outer end of the trunnion they are carried up and out of the stream by the blades or ribs 18. The trunnion and ribs being approximately horizontal, as preferably they are, the material 35 carried up and out of the stream is no longer urged forward by material behind it and hence, except for the momentum already achieved, would have as great a tendency to flow back into the mill as to flow out into 40 the launder 17. Hence the rate of flow toward the outlet end of the trunnion is lessened rather than increased, with the result that most of the larger particles would be carried a considerable distance up with the 45 ascending side of the trunnion before escaping. At a suitable point, for example just above the horizontal diameter thereof, is a jet pipe 19, connected with any convenient source of water, compressed air, or other 50 suitable fluid not shown, and directed toward the ascending side of the trunnion and also slightly downward. The more or less powerful jet of water discharged from this pipe strikes the material carried up by 55 the ascending channels and washes it back into the barrel 10, where the material is engulfed in the violently churning or agitated contents of the revolving barrel. In this way the greater part of the coarse material 60 which finds its way into the outlet trunnion is returned to the barrel, while most of the slime flows out of the trunnion before the ascending ribs reach the path of the water jet. In other words, the slime discharged 65 into the launder 17 contains only a

small proportion of coarse particles, while the coarse particles washed back into the barrel are accompanied by only a relatively small amount of slime. Hence the efficiency of the apparatus is not decreased, but in fact may be actually increased, since the outflow, though slightly reduced in volume, 70 contains fewer particles that cannot be advantageously utilized (if utilizable at all) because of their excessive size. Of course if 75 the jet pipe 19 discharges outwardly the particles carried up by the ascending side of the trunnion will be washed out of the barrel instead of back into it.

It is to be understood that the invention is 80 not confined to the construction herein specifically illustrated, but can be embodied in other forms without departure from its proper spirit and scope.

What I claim is:

85

1. In an apparatus for the purpose set forth, a rotary tubular outlet member for the outflow of disintegrated material, having on its inner surface a plurality of channels extending in a generally longitudinal 90 direction, and means above the outflowing material for discharging fluid into the channels in a direction opposite to that of the outflowing material.

2. In an apparatus for the purpose set 95 forth, a rotary tubular outlet member for the outflow of disintegrated material having on its inner surface a plurality of channels extending in a generally longitudinal direction, and a jet pipe arranged to discharge fluid inwardly into the channels above the surface of the material flowing out through said tubular member as the latter rotates.

3. In an apparatus for the purpose set 105 forth, a rotary tubular outlet member having on its inner surface a plurality of ribs extending in a generally longitudinal direction, and a jet pipe above the bottom of the outlet member and at the ascending side 110 of the same, arranged to direct a jet of fluid into the channels formed by said ribs as they pass the outlet orifice of said pipe.

4. The combination with a rotary receptacle having a rotary tubular outlet member, of means for directing a jet of fluid in a substantially axial direction upon the ascending side of the member inside the same.

5. The combination with a rotary grinding mill having a rotary outlet member, of 120 means revolving with the outlet member inside the same to separate coarse particles from the disintegrated material flowing out through said member, and a jet pipe arranged to discharge a jet of fluid upon the 125 said coarse particles and propel the same back into the grinding mill.

6. The combination with a rotary grinding mill, a rotating tubular outlet member therefor having on its inner surface a plu- 130

rality of longitudinally extending channels, and a jet pipe arranged to discharge a jet of fluid backwardly into said channels after they have passed the bottom of their path 5 and as they are rising with the ascending side of the outlet member.

In testimony whereof I affix my signature in the presence of two subscribing witnesses.

HARRY W. HARDINGE.
